MARCELLUS EUGENE SMITH, OF LOS ANGELES, CALIFORNIA, ASSIGNOR OF ONE-EIGHTH TO DALE D. HALE, OF LOS ANGELES, CALIFORNIA, AND ONE-EIGHTH TO RAY M. HALE, OF LAS VEGAS, NEVADA

AIRPLANE PROPELLER

Application filed May 17, 1932. Serial No. 611,781.

This invention relates to a propeller and more particularly pertains to a propeller of the spiral or helical blade type.

An object of the invention is to provide a propeller embodying a construction whereby the fluid in the zone acted on by the propeller blades will be densified relative to surrounding fluid as the propeller advances thereinto, and to provide a form and arrangement of a plurality of propeller blades whereby the blades on being rotated will advance spirally into the densified zone of fluid and each blade present an effective operating surface throughout a distance of at least one half a convolution.

Another object is to provide a propeller of the above character in which the spirally disposed blades may be adjusted to vary their spiral pitch, and embodying a construction whereby corresponding adjustment of a plurality of the blades may be effected to insure cooperating blades having equal pitch in the various adjusted positions.

Another object is to provide an effective means for securely retaining the blades in a fixed position relative to a cylinder and in their adjusted positions to insure against accidental displacement thereof.

Another object is to provide a propeller which is so formed that when advancing into the fluid the pressures generated thereby will serve to assist in effecting rotation of the propeller.

Another object is to provide a propeller which is particularly advantageous for use in the propulsion of air craft, and which is especially adapted for operation at high speeds, with the employment of a minimum of mechanical power.

Another object is to provide a propeller of the spiral type embodying a construction whereby helical blades may be disposed at various spiral arrangements around a cylinder without the formation of gaps between the outer periphery of the cylinder and contiguous portions of the blades.

With the foregoing objects in view, together with such other objects and advantages as may subsequently appear, the invention resides in the parts, and in the combi-

nation, construction and arrangement of parts hereinafter described and claimed and illustrated by way of example in the accompanying drawing, in which:

Fig. 1 is a view of the propeller as seen in front elevation; 55

Fig. 2 is a view in side elevation; 58

Fig. 3 is a view in longitudinal section taken on the line 3—3 of Fig. 1; 60

Fig. 4 is a view in cross section as seen on line 4—4 of Fig. 3; 60

Fig. 5 is a view in section and elevation as seen on the line 5—5 of Fig. 3; 65

Fig. 6 is a detail in section taken on the line 6—6 of Fig. 4, with parts shown in plan. 65

Referring to the drawing more specifically, A indicates the propeller generally, which embodies a hollow cylinder B from the outer periphery of which projects at least a pair of blades 10 and 11 each of which extends spirally around at least half the circumference of the cylinder, each of the blades thus being approximately a half convolution in length; the blades 10 and 11 extending from opposed halves of the cylinder at opposite inclinations with their adjacent ends spaced apart and slightly overlapping each other. The outer edges of the blades are formed on arcs concentric with the axis of the cylinder so as to collectively present an annular wall 70 around the cylinder. The protruding portions of the blades are tapered in cross section, as shown in Fig. 3, and the leading or entrant ends of the blades are curved outwardly, as indicated at 12, while the trailing ends are curved rearwardly away from the back of the adjacent leading end of the other blade, as indicated at 13. 75

The cylinder B is composed of a pair of annular walls 14 and 15 which are spaced apart to form a slot C circumferentially of the cylinder B through which the blades extend, the walls 14 and 15 being detachably secured to flanges 16 and 17 formed on plates 18 and 19 as by screws 20 and 21. A drive shaft D extends axially of the cylinder B and has a tapered outer end portion on which is mounted a hub 22 carrying the plates 18 and 19 which latter are spaced apart. The outer end of the shaft is formed with a threaded 80

85

90

95

100

stem 23 on which is screwed a nut 24 whereby the hub is clamped on the shaft in engagement with a key 25 on the latter. The cylinder is thus affixed to the shaft to rotate therewith. Projecting diametrically from the hub 22 are axially aligned trunnions 26 and 27 on which the blades 10 and 11 are pivotally carried at the longitudinal centers thereof, whereby the blades may be turned 10 to extend diagonally through the slot C at various angles so that the pitch of the blades may be varied as occasion may require.

Means are provided for collectively shifting the blades around their pivotal connection with the trunnions, which means is here shown as comprising a screw E revolvably carried by the plates 18 and 19 and extending through sleeves 28 and 29 pivotally supported in openings 30 and 31 formed on overlying 15 inner end portions of the blades 10 and 11; the sleeves being carried on pivots 32. The screw E is formed with correspondingly pitched right and left threads 33 and 34 at its opposite end portions, engaging the sleeves 20 28 and 29 so that on turning the screw the adjacent overlying ends of the blades 10 and 11 will be moved in opposite directions. A head 35 is formed on one end of the screw E and is arranged forward of the plate 18 25 whereby the screw may be engaged by a suitable tool and rotated thereby to effect adjustment of the blades. The screw E is held against longitudinal movement relative to the plate 18 by the head 35 and a collar 36 which 30 latter abuts against the inner face of the plate 18.

As a means for securely holding the blades in their adjusted position a series of bolts 37 and 38 are screwed through the plates 18 and 40 19 to abut against the opposite sides of the inner portions of the blades; the bolts being advanced or retracted as need be either to permit swinging movement of the blades or to 45 clamp the blades against movement.

As a means for maintaining the slot C closed, the blades 10 and 11 are fitted with laterally projecting flanges 39 and 40 which underlie the adjacent margins of the rings 14 and 15 in sliding contact therewith, the 50 outer faces of which flanges are formed on a segment of a sphere whereby on swinging the blades on the trunnions to various positions the outer faces of the flanges will at all times abut against the inner faces of the rings; the 55 arcuate outer surfaces of the flanges extending concentric with the point of intersection of the axis of the cylinder B with the axis of the trunnions 26 and 27.

Mounted on the forward end of the cylinder B is a cone F which is demountably attached to the cylinder as by screws 42 and which cone constitutes a fairway and serves on advance of the propeller into a fluid to displace the fluid and thereby form a densified 65 zone of the fluid on which the blades act.

The shaft D extends rearwardly of the cylinder B and connects with a suitable motor (not shown) in a usual manner, and encompassing the shaft is a drum G having an outside diameter substantially corresponding to 70 that of the cylinder, and which drum leads rearwardly from the back end of the cylinder B any suitable distance to the motor supporting structure.

In the operation of the invention the blades 75 10 and 11 are disposed in their desired angular relation to each other by means of the screw E as before described; swinging of the blades on the trunnions serving to vary their spiral relation to the cylinder B. On rotating 80 the shaft D the cylinder B together with the blades 10 and 11 will be caused to revolve. The blades being disposed diagonally or spirally relative to the axis of the revolving cylinder will effect a screw action of 85 the fluid in which the blades revolve, the entrant or leading ends of the blades moving at an angle into the surrounding fluid serving to direct the fluid contacted thereby rearwardly thereby tending to pull the propeller 90 and its attached structure forwardly.

When the propeller advances, the cone F acts to densify the fluid flowing to the blades so that the latter will act on a denser volume 95 of the fluid than otherwise. A pressure is thus built up forward of the blades which because of the inclinations of the latter will assist in effecting rotation of the propeller.

I claim:

1. In a propeller, a hollow cylinder formed 100 with a circumferentially extending slot, a drive shaft on which said cylinder is mounted, axially aligned trunnions projecting diametrically from opposite sides of said shaft, blades carried on said trunnions and projecting through said slot with their outer portions protruding from said cylinder in a spiral relation thereto throughout a half convolution, and projecting flanges on said 105 blades closing said slot.

2. In a propeller, a hollow cylinder formed with a circumferentially extending slot, a drive shaft on which said cylinder is mounted, axially aligned trunnions projecting diametrically from opposite sides of said shaft, blades carried on said trunnions and projecting through said slot with their outer portions protruding from said cylinder in a spiral relation thereto throughout a half convolution, and projecting flanges on said blades 115 closing said slot, the outer faces of said flanges being formed on a segment of a sphere and seating on the inner margins of said slot.

3. In a propeller, a hollow cylinder formed with a circumferentially extending slot, a 125 drive shaft carrying said cylinder, axially aligned trunnions carried by said shaft, blades on said trunnions protruding diagonally through said slot with their outer portions projecting from the outer periphery of 130

said cylinder and each blade extending throughout one half the circumference of said cylinder, flanges on said blades closing said slot, and means for adjusting said blades 5 to various positions transversely of said slot to vary the diagonal pitch thereof.

4. In a propeller, a hollow cylinder formed with a circumferentially extending slot, a drive shaft carrying said cylinder, 10 axially aligned trunnions carried by said shaft, blades on said trunnions protruding diagonally through said slot with their outer portions projecting from the outer periphery of said cylinder and each blade extending 15 throughout one half the circumference of said cylinder, flanges on said blades closing said slot, means for collectively adjusting said blades to various positions transversely of said slot to vary the diagonal pitch thereof, 20 and means cooperating with said last named means to secure said blades against turning on said trunnions.

5. In a propeller, a cylinder formed with a circumferentially extending slot, a drive 25 shaft on which said cylinder is mounted, a plurality of blades carried by said drive shaft protruding through said slot, means for adjusting said blades to various positions transversely of said slot, and means carried by said 30 blades closing said slot.

MARCELLUS EUGENE SMITH.
